UNITED STATES PATENT OFFICE.

SIGFRID A. MILLER, OF OAKLAND, CALIFORNIA.

AUTO BED.

Application filed March 11, 1920. Serial No. 364,939.

To all whom it may concern:

Be it known that I, SIGFRID A. MILLER, a citizen of the United States, residing at Oakland, in the county of Alameda and 5 State of California, have invented a new and useful Improvement in Auto Beds, of which the following is a specification.

This invention relates to an auto bed and especially to improvements on the bed structure shown in my former Patent No. 1,276,095, entitled "Auto bed," issued 10 August 20, 1918.

One of the objects of the present invention is to provide a simple, substantial, 15 cheaply manufactured folding bed for automobiles and the like, which is adapted to be secured to the running board in such a manner that it may be readily extended outwardly when used or folded up on the 20 running board in a compact unit when travelling.

Another object of the invention is to provide a mattress frame of novel construction which is foldable and which is provided 25 with legs and braces for its support when extended, and also with a tent support which permits the bed to be enclosed or covered when desired.

Another object of the invention is to provide a head board which is so positioned and connected that it is automatically folded or extended in unison with the bed, and which serves two separate functions; first, that of a head board for the support of pillows, etc., 35 when the bed is extended, and secondly, it is adapted to cooperate with the foot frame to support the mattress and bedding when the bed is folded and which supports the mattress and bedding above the running 40 board and out of contact with the same at all times.

Another object of the invention is to provide a novel pivotal connection between the folding sections of the bed frame as will 45 hereinafter be described.

Further objects will hereinafter appear.

The invention consists of the parts and the construction, combination and arrangement of parts as hereinafter more fully described and claimed, having reference to the 50 accompanying drawings, in which—

Fig. 1 is a perspective view of the bed showing it extended with relation to the running board of an automobile.

Fig. 2 is a perspective view showing the 55 bed in folded position upon the running board of an automobile.

Fig. 3 is an end view of the head end of the bed.

Fig. 4 is a detail side elevation of one of 60 the bed securing clamps.

Fig. 5 is a perspective view illustrating one of the pivotal connections formed between the several folding sections of the 65 bed frame.

Referring to the drawings in detail, A indicates in general a folding bed, the frame of which consists of three sections such as indicated at 2, 3 and 4. These sections will hereinafter be referred to as the inner 70 section, the intermediate section and the outer section. The sections 2 and 4 are pivotally attached to the intermediate section as indicated at 5 and are foldable thereabout to assume the position shown in Fig. 75 2, or the extended horizontal position shown in Fig. 1. The detailed construction of the pivotal connections 5 is more clearly illustrated in Fig. 5. By referring to this figure it can be seen that the three separate 80 sections are constructed of angle iron and that the inner and outer sections are provided with extending rounded lugs 6, through which the pivotal connections 5 extend. The outer end of each lug 6 is flat 85 as at 7 and forms a lock with the horizontal portion 8 of the intermediate section 3 when a vertical position is assumed as shown by dotted lines at 9. This is of importance as it limits the pivotal movement 90 between the several sections, for instance, the shoulder 7 locks against movement when a right angular position is assumed, while an offset 10, formed in the sections 2 and 4, forms a stop shoulder which locks 95 against further movement when a horizontal position is reached. Another important feature is the fact that the pivotal connection 5 is formed in direct alignment with the stop shoulder 10, thus reducing the lever or 100 shear strain to which the pivots 5 would otherwise be subjected.

The bed frame as a whole is attached to the running board by means of a pair of screw clamps 11 and as these screw clamps 105 are pivotally attached to the bed frame as at 12, it should be obvious that the bed frame may be folded into the position

shown in Fig. 2. For the purpose of supporting the bed when extended, legs such as shown at 14 are provided, one set of legs being pivotally attached as at 15, where the 5 inner and intermediate bed frame sections are connected, while the other set of legs are pivotally attached to the outer frame section at the point indicated at 16. The legs 14 may be folded up into alignment with 10 the respective bed frame sections, but are thoroughly braced and secured when unfolded as shown in Fig. 1 by folding links 17 and a spacing link 18. The bed is also provided with an auxiliary set of legs, 15 shown at 19. These are pivotally attached to the head end of the bed and may be folded with relation thereto when not required. They are otherwise secured in their extended position by folding links as at 20. 20 The legs 19 are merely employed when it is desired to remove the bed with relation to the foot board which may happen, for instance, when staying in a permanent camp for a few days or the like, as it may 25 be desirable to use the machine from time to time during a more or less prolonged stay in a certain place. Hence the reason for providing the auxiliary legs such as shown at 19.

30 The bed is provided with a foot frame 21 and with a head frame or board 22. The foot frame 21 consists of an upright section 23, which is connected by means of cross bars 24. The upright sections are 35 bent at right angles at their lower ends, and the frame as a whole is pivotally attached to the outer bed frame section, as at 25. The right angular extensions formed on the lower end of the foot frame have a 40 length exactly half that of the intermediate frame section 3, and it therefore assumes a central position between the main bed frame sections 2 and 4 when the bed is folded as shown in Fig. 2. The foot frame 45 forms two important functions besides that of a foot frame. First a support for a tent or canopy covering 26. Secondly a mattress clamp when the bed is to be folded. And third, a mattress hanger which as- 50 sumes a vertical position when the bed is folded as shown in Fig. 2. The foot frame is held in an upright position when the bed is extended as illustrated in Fig. 1, by means of a pair of brace links 27. These 55 links are pivotally attached to the bed frame section 4 as at 28, and their opposite ends are hook shaped as at 29. The hook shaped ends of the bracing links engage pins 30 on the foot frame section when this 60 is raised to an upright position, thereby securing the same against collapsing when the tent or canopy 26 is secured thereto. The links 27 also serve another function, to-wit, that of securing the bed frame sec- 65 tions 2 and 4 against separating when

folded as the hook ends are then swung into engagement with pins 31, which are carried by the bed frame section 2.

The head board extends crosswise of the head end of the bed (see Fig. 2.) and it is 70 attached thereto by means of a pair of links 32. These links are pivotally attached to the inner side of the bed frame section as at 33 and the head board is in turn pivotally connected to the outer free end of said 75 links as at 34. The links are so short that the inner end of the foot board will engage the main cross bar or end section of the bed frame 2 and it will therefore assume an angular position when the bed is extended, 80 and it will assume a horizontal position on top of the running board of the automobile as shown at 35 when the bed frame is folded. The head board serves two important 85 functions, first that of supporting pillows, etc., when the bed is extended, and secondly that of supporting the mattress, pillows and bedding when the bed is folded, and furthermore in such a position that a space is formed between the head board 90 and the running board, thus excluding dust to a large extent and preventing wetting of the bedding in case of rainy weather, that is water collecting on the running board can freely run off and will at no time come 95 in contact with the bedding, due to the spacing formed between the head board and the running board, the spacing being maintained due to the fact that the board rests on top of the clamps 11 by which the bed 100 as a whole is attached to the running board.

The canopy 26 employed may be so constructed that it entirely incloses the bed, and it is obvious that it may be supported in any manner desired as this forms no 105 part of the present invention. For instance it may be attached to the auto top as shown at 40, and its opposite end may be secured in any suitable manner to the foot frame 21. The canopy may or may not be em- 110 ployed as conditions or individuals may require.

To thoroughly brace the bed when in an extended position, I employ a cross frame 41. This frame is offset as shown to prevent interference with the spring mattress shown at 42, and while it may be secured in any suitable manner, I have here shown it attached to the pivotal connection 5 by which the intermediate section 3 is connected with the inner bed frame section 2. This feature, together with the construction and arrangement of the legs 14, is of comparatively little importance in the present case as it is covered and forms the subject 115 matter of my former patent previously referred to, the important features of the present invention being the specific construction of the brake joint or connection 120 between the bed frame sections and the 125 130

construction and attachment of the foot and head frames described, and as these are more or less specifically illustrated, I wish it understood that various changes in form and proportion may be resorted to within the scope of the appended claims, similarly that the materials and finish of the several parts employed may be such as the experience and judgment of the manufacturer 5 may dictate or varying conditions may demand.

Having thus described my invention, what I claim and desire to secure by Letters Patent is—

15 1. In a folding bed of the character described a bed frame consisting of an intermediate section, an inner section and an outer section, a foot frame, a right angular extension on the bottom portion of the foot 20 frame, a pivotal connection between the foot frame and the outer bed frame section, pivotal connections between the inner bed frame section, the outer bed frame section and the intermediate section, permitting 25 folding movement of the several sections with relation to each other, and folding movement of the foot frame with relation thereto, so that it will assume an intermediate position between the bed frame sections 30 and serve as a hanger for the support of the mattress and bedding.

2. In a folding bed of the character described a bed frame consisting of an intermediate section, an inner section and an outer section, a foot frame, a right angular extension on the bottom portion of the foot frame, a pivotal connection between the foot frame and the outer bed frame section, pivotal connections between the inner bed frame 35 section, the outer bed frame section and the intermediate section, permitting folding movement of the several sections with relation to each other, and folding movement of the foot frame with relation thereto, so 40 that it will assume an intermediate position between the bed frame sections and serve as a hanger for the support of the mattress and bedding, a head board, and a pair of links pivotally connected at one end to said 45 head board, and at their opposite ends to the head end section of the inner bed frame section.

3. In a folding bed of the character described a bed frame consisting of an intermediate section, an inner section and an outer section, a foot frame, a right angular extension on the bottom portion of the foot frame, a pivotal connection between the foot frame and the outer bed frame section, 55 pivotal connections between the inner bed frame section, the outer bed frame section and the intermediate section, permitting folding movement of the several sections with relation to each other, and folding 60 movement of the foot frame with relation

thereto, so that it will assume an intermediate position between the bed frame sections and serve as a hanger for the support of the mattress and bedding, a head board, a pair of links pivotally connected at 70 one end to said head board, and at their opposite ends to the head end section of the inner bed frame section, a support to which the inner bed frame section is pivotally attached, and means for maintaining a spacing between said support and the head board. 75

4. In a folding bed of the character described a bed frame consisting of an intermediate section, an inner section and an outer section, a foot frame, a right angular 80 extension on the bottom portion of the foot frame, a pivotal connection between the foot frame and the outer bed frame section, pivotal connections between the inner bed frame section, the outer bed frame section 85 and the intermediate section, permitting folding movement of the several sections with relation to each other, and folding movement of the foot frame with relation thereto, so that it will assume an intermediate 90 position between the bed frame sections and serve as a hanger for the support of the mattress and bedding, a head board, a pair of links pivotally connected at one end to said head board, and at their opposite ends to the head end section of the inner bed frame section, a pair of clamps pivotally attached to the inner bed frame section, and a support for said clamps, said 95 clamps adapted to serve as a spacer between the head board and the support.

5. In a folding bed of the character described a bed frame consisting of an inner section, an intermediate section and an outer section, pivotal connections between said 105 sections permitting the sections to assume a horizontal position, and also permitting the inner and outer sections to assume a vertical position, and the intermediate section to assume a horizontal position when folded, a 110 foot frame pivotally attached to the foot end of the outer bed frame section, and an offset section on the foot frame causing it to assume an intermediate position between the inner and outer bed frame sections when 115 folded.

6. In a folding bed of the character described a bed frame consisting of an inner section, an intermediate section and an outer section, pivotal connections between said 120 sections permitting the sections to assume a horizontal position, and also permitting the inner and outer sections to assume a vertical position and the intermediate section to assume a horizontal position when folded, a 125 foot frame pivotally attached to the foot end of the outer bed frame section, an offset section on the foot frame causing it to assume an intermediate position between the inner and outer bed frame sections when 130

folded, and a pair of bracing links pivotally attached to the outer bed frame section, said links adapted to lock the foot frame in position when the bed is extended and said bracing links adapted to lock the bed frame sections against separation when folded.

7. In a folding bed of the character described, a bed frame consisting of an inner section, an intermediate section and an outer section, pivotal connections between said sections permitting the sections to assume a horizontal position, and also permitting the inner and outer sections to assume a vertical position, and the intermediate section to assume a horizontal position when folded, a foot frame pivotally attached to the foot end of the outer bed frame section, an offset section on the foot frame causing it to assume an intermediate position between the inner and outer bed frame sections when folded, a pair of bracing links pivotally attached to the outer bed frame section, hook shaped ends on said links, pins on the foot frame with which said hooked ends are engageable to lock the foot frame in vertical position when the bed is extended, and pins on the sides of the inner bed frame section with which the hooked ends and the links are engageable to lock the bed frame sections against separation when in folded position.

8. In a folding bed of the character described the combination with the inner bed frame section, of a head board, a pair of links pivotally attached at one end to the head board and at their opposite ends to the inner bed frame section, and a head bar extending crosswise of the inner bed frame section adapted to support the inner end of the head board, said head board extending over the head bar and said links being so short that the head board will assume an

angular position with relation to the inner bed frame section when this is extended and permitting the head board to assume a horizontal position when the bed frame is folded.

9. In a folding bed of the character described the combination with the inner bed frame section, of a head board, a pair of links pivotally attached at one end to the head board and at their opposite ends to the inner bed frame section, a head bar extending crosswise of the inner bed frame section adapted to support the inner end of the head board, said head board extending over the head bar and said links being so short that the foot board will assume an angular position with relation to the inner bed frame section when this is extended and permitting the head board to assume a horizontal position when the bed frame is folded, a support, and a pair of screw clamps pivotally attached to the bed frame adapted to secure the frame to the support, said clamps being engageable with the head board to maintain a spacing between the head board and the support when folded.

10. In a folding bed of the character described, the combination with the inner bed frame section, of a head board, a pair of links pivotally attached at one end to the head board and at the opposite ends to the inner bed frame section, and a head bar extending crosswise of a corresponding end of the bed frame section adapted to support the head board.

In testimony whereof I have hereunto set my hand in the presence of two subscribing witnesses.

SIGFRID A. MILLER.
